UNITED STATES PATENT OFFICE

FREDERICK A. HART, OF NEW BRITAIN, CONNECTICUT, AND SIGURD L. WALSOE, OF LYNDHURST, NEW JERSEY, ASSIGNORS TO REMINGTON TYPEWRITER COMPANY, OF ILLION, NEW YORK, A CORPORATION OF NEW YORK

TYPEWRITING MACHINE

Application filed September 23, 1927. Serial No. 221,543.

Our invention relates to typewriting or like machines and more particularly to work sheet controlling means and associated devices to aid in rapidly and accurately inserting and collating in the machine various combinations of work sheets for bookkeeping, billing and other work.

One of the main objects of our present invention is to provide improved means of the character specified which facilitate a carrying out of the work with great rapidity, with little chance for faulty operation on the part of the operator, with an assurance of mechanical accuracy in the collating operation and which require but a few simple operations, free in the main from the exercise of judgment, in order to properly manipulate the machine.

The present invention is in the nature of improvements on the so-called "Remington front feed bookkeeping machine", and on a machine such as is disclosed in the application of Sigurd L. Walsoe, Sr. No. 195,321 filed May 31, 1927 (now Patent No. 1,714,063 dated May 21, 1929). The present invention is intended to improve such machines by widening the scope of their uses; to provide for a ready adjustment of various parts that enable the machine to be more readily employed on work sheets of various widths; to provide a construction in which fewer operations are required to manipulate the machine and in which the proper relation of the parts required at certain times is attained with less effort on the part of the operator and with a greater assurance of accuracy than formerly, and in which virtually a universal billing mechanism of the character specified is provided.

To the above and other ends which will hereinafter appear, our invention consists in the features of construction, arrangements of parts and combinations of devices set forth in the following description and particularly pointed out in the appended claims.

In the accompanying drawings wherein like reference characters designate corresponding parts in the different views:

Figure 1 is an enlarged, detail, fragmentary, side elevation, with parts broken away

and in section, of enough of a "Remington front feed bookkeeping machine" to illustrate our invention in its embodiment therein; the view showing the parts as they appear when the machine is conditioned to proceed with the writing, except that the work sheets are not shown in place.

Figure 2 is a plan view of the same.

Figure 3 corresponds to Fig. 1 except that the parts in Fig. 3 are shown disposed as they appear when the machine is conditioned to receive a new, say, ledger sheet.

Figure 4 is a view corresponding to Fig. 3 but showing the parts disposed as they appear after the outside margin feed rollers, the front deflector and the line indicator have been simultaneously shifted from the Fig. 3 to the Fig. 4 position with the aid of the secondary finger piece 59.

Figure 5 is an enlarged, detail, fragmentary horizontal sectional view of a portion of the machine taken on the line 5—5 of Fig. 1 and looking in the direction of the arrows at said line.

Figure 6 is a detail, fragmentary side view, with parts in section, of the means for supporting and controlling the ribbon vibrator.

Figure 7 is an enlarged, detail, vertical, transverse sectional view of one of the adjustable spring-pressed supports for a feed roller and some of the associated parts, the section being taken on the line 7—7 of Fig. 8 and looking in the direction of the arrows at said line.

Figure 8 is an enlarged, detail, vertical, fore and aft sectional view taken on the line 8—8 of Fig. 7 and looking in the direction of the arrows at said line; the view illustrating one of the intermediate feed rollers withdrawn and the means for mounting and controlling it.

Figure 9 is an enlarged, detail, fragmentary, horizontal sectional view of the same, showing the feed roller applied to the platen; the section being taken on the line 9—9 of Fig. 8.

Figure 10 is an enlarged, detail, side view, with parts in section, showing one of the

toggle arms of an outer feed roller mounted to turn with the rock shaft.

Figure 11 is a like view showing one of the toggle arms of an intermediate feed roller free to turn on the rock shaft.

Figure 12 is a detail, fragmentary, transverse sectional view with parts broken away, taken on the line 12—12 of Fig. 13 and looking in the direction of the arrows at said line; the view showing another form of construction in which the toggles for the feed rollers 70 are connected to apply said feed rollers in unison.

Figure 13 is a detail, fragmentary plan view of the construction disclosed in Fig. 12.

As in the said Remington machine and also that disclosed in said previously filed application, the present machine is capable of a wide range of uses in connection with various so-called billing operations and the like, where two or more work sheets are to be correlated and printed at a single operation. However, we do not deem it necessary to describe specifically the many different forms of billing operations in which the machine may be used. It is sufficient for an understanding of the present invention to specifically describe one mode of billing that may be successfully carried out with the aid of the present machine, and perhaps briefly refer to some of the various other methods in connection with which the machine may be employed.

One method of using the machine, which will be specifically referred to, is its employment for simultaneously, or at one writing, making out a bill or "statement", making corresponding entries on the ledger sheet carrying the account, and on a record or register sheet which receives the various entries written on all of the individual statement and ledger sheets. In the example referred to the register sheet and its accompanying carbon sheet remain in the machine. Means are provided to enable the ledger sheet and its accompanying carbon sheet to be quickly introduced and properly positioned to receive the requisite entries without disturbing the previously introduced register sheet and companion carbon sheet. Means also are provided for then quickly entering a statement sheet into the machine in front of the platen and accurately positioning it in proper correlation with the previously introduced ledger sheet and the printing line. The entries may then be made on the statement sheet and these will be transferred through the interposed carbon sheets to the ledger and register sheets. If desired, additional entries may be made on the ledger sheet which are not to appear on the statement or register sheet. The statement and ledger sheets are then rapidly withdrawn from the machine without disturbing the register sheet and its companion carbon sheet.

and another ledger sheet and statement sheet may then be quickly introduced, as before, and so on.

A line spacing operation effected by the return of the carriage after writing a statement and making the corresponding entry on the ledger and register sheets, advances the register sheet in position to receive a manifold copy of the next entry on the register sheet.

With the foregoing general explanation of the purpose and operation, we will proceed to describe the invention as it is embodied, in the present instance, in said hereinbefore mentioned Remington machine.

The frame of the machine includes the usual top plate 1 supporting fixed guide rails 2. The carriage or truck comprises front and rear guide or cross bars 3, united by end bars 4 and 5. The guide rails 2 and cross bars 3 are oppositely grooved to receive crossed anti-friction rollers 6 by which the carriage is supported in the usual manner to travel from side to side of the machine over the top plate 1.

A cylindrical platen 7 is mounted in the usual manner in a platen frame comprising the rigidly connected end plates 8 and 9; the platen frame being connected to the carriage by the usual shift links 10 and 11. In the present instance, however, we contemplate writing only with upper case characters and the platen is, therefore, preferably held in the upper case position. This may be readily done by screwing up the lowermost case-shift limiting screw-stops 12, thereby holding the platen shaft, or the buffer springs 13 which surround it, against the upper case limiting stops 12. This brings the printing line on the platen to a position where the uppermost types on the usual type bars will register therewith.

A ribbon vibrator 17 is mounted to slide up and down in the usual manner on a type bar center guide 18 secured to the type bar segment 19. The vibrator is actuated at each printing operation by the usual mechanism (see Fig. 6), which includes an arm 20. Said arm is pivoted at 21 on a shiftable carrier or support 22 mounted on parallel links 23. A contractile spring 24 tends to lift the shiftable support 22, and causes an anti-friction roller 25 carried thereby to bear upward against the lower edge of a bar 26. This bar is secured to the carriage and extends substantially throughout the length thereof. In the standard Remington machines the purpose of this construction is to cause the ribbon vibrator to be shifted up and down with the platen in the case shifting movements of the latter. In the present construction there is no such case shifting movements of the platen but the construction, nevertheless, lends itself to the accomplishment of another result which will hereinafter appear.

As in the construction disclosed in said

previously filed application it is desirable when introducing a work sheet backwardly into the machine to lower the ribbon vibrator from its normal, Fig. 1, position. This is in order to enable the front paper deflector to be more conveniently moved to effective position, as shown in Fig. 3. In the present construction we have employed the same means that are disclosed in said hereinbefore mentioned application for effecting this result. Thus, as in the prior construction, a bracket arm 27 extends forward from the shiftable support 22 and carries an anti-friction roller 28 at the upper end thereof. A rock shaft 29 extends throughout the length of the carriage and is mounted at its ends in bearing openings in the end plates 8 and 9 of the platen frame. This rock shaft 29 carries a plate 30 which extends substantially throughout the length thereof and is bent down at its forward edge to form a flange 31 which coacts with the anti-friction roller 28. When the rock shaft 29, and the plate 30 carried thereby, are shifted by means to be hereinafter described, from the Fig. 1 to the Fig. 3 position, the shiftable support 22 will be lowered against the power of its spring 24, effecting a corresponding lowering of the ribbon vibrator 17 from its normal position.

Coming now to the means for controlling and guiding the work sheets, it will be observed in the first place that there are no paper feed rollers employed beneath the platen, such rollers as are employed being located above the printing line, leaving the space beneath the platen free for the use of other devices.

As in said prior constructions there are two curved paper deflectors 32 and 33 employed beneath the platen, one arranged above the other and maintained spaced apart by intermediate spacing members or blocks 34 and 35 located near the ends thereof. Generally speaking, these deflectors conform to the curvature of the platen or are substantially concentric therewith and extend substantially throughout the length of the platen. As thus constructed there are two separate channels provided, one of which is the open channel 36 between the two deflectors and which is bounded at its ends by separating members 34 and 35, either or both of which may constitute side guides or gages for cooperation with a work sheet or sheets introduced into the channel 36. The other separated channel 37 is provided between the under surface of the platen and the upper deflector 32. The forward edge of the deflector 33 terminates in advance of the forward edge of the deflector 32, and has a slight downward curve in cross section. The deflector 33 is continued up at the rear to provide an upwardly and rearwardly extending paper table 38 which terminates at a considerable height above the platen. On the

other hand, the deflector 32 terminates in the rear of the platen at a much lower point and below the top of the platen, where it is bent to form a loop 39 that loosely surrounds a rod 40 fixedly connected at its ends to the end plates 8 and 9 of the platen frame. In this manner the rigidly united deflectors 32 and 33 are mounted on the rod 40 and have a slight controlled pivotal movement thereon.

Suitable adjustable means, which for the purpose of the present invention it is unnecessary to describe, may be employed to hold the double deflector 32-33 against pivotal movement around the rod 40 and with the front edge of the deflector 32 arranged close to the platen, as shown. In this manner the sheets introduced from the rear of the platen through the channel 37 will be held snugly against the platen, and the sheets introduced into the channel 36 will be prevented from entering the channel 37.

In order to facilitate the backward introduction of the work sheets into the mouth of the channel 36 from in front of the platen, there is provided a guide, shield, or front paper deflector 47 that is movable on the carriage from a substantially horizontally disposed ineffective position, shown in Fig. 1, to a downwardly and rearwardly inclined effective position, shown in Fig. 3, and vice versa, as disclosed in said previously filed application. In order to receive these movements the deflector is constructed and mounted, in the present instance, in the specific manner disclosed in said previously filed application.

Thus the sheet metal deflector 47, which extends substantially throughout the length of the platen, is carried by parallel sheet metal supporting arms 48 and 49. These supporting arms are pivotally mounted on forwardly projecting arms 50 secured to the end plates 8 and 9 of the platen frame and which may be regarded as parts of said end plates. The left-hand pivot pin 51, on which the arm 48 turns, supports a bell crank lever 52 one arm of which carries a pin 53 by which a detachable connection is made with the arm 48. The other arm 54 of the lever 52 carries an outwardly projecting connecting pin 55 that is received and works in a slotted cam 56 in an actuating arm 57. Said arm 57 is provided with a hub 58 (see Fig. 1) by which it is secured to the hereinbefore mentioned rock shaft 29 by a set screw 58a. The character of the slotted cam and the construction and the arrangement of the parts are such that a forward pivotal movement of the arm 57 from the Fig. 1 to the Fig. 3 position, causes a pivotal movement of the deflector 47 in the opposite direction, or rearwardly from its normal ineffective position. This brings the deflector 47 to the effective position, shown in Fig. 3, where it overlaps and virtually forms a continuation of the deflector 33. In this

movement of the deflector 47 it passes from a position where it is out of the path of the type bars to a position where it is in the path thereof, and crosses the printing line 5 where it is effective in directing work sheets introduced rearward from in front of the platen downward into the open channel 36. From thence the sheets in question pass around and beneath the platen.

- 10 The actuating arm 57 is provided with a so-called secondary or auxiliary finger piece 59 at the upper end thereof, whereby said arm and the parts controlled thereby may be actuated at will. The arm 57 also stands in 15 cooperative relationship with means for controlling the shifting movement of certain of the feed rollers, to be automatically controlled thereby, and also to control such feed rollers, as will hereinafter clearly appear.
- 20 The actuating arm 57 constitutes one of two supporting arms for a wire line-indicator 60. Said indicator extends longitudinally throughout the length of the platen and is adjustably connected to the arm 57 by 25 means of two clamping jaws 61 and 62, as disclosed in said prior application. The opposite end of the line indicating wire may be adjustably secured to a second supporting arm 63 (see Fig. 1), the arm 30 63 being secured to the rock shaft 29 near the right-hand end thereof. A coiled contractile spring 64 is connected at one end to the arm 57 and at its opposite end to a pin 65 extending inward from the end plate 8. 35 This spring tends to return the arm 57 and the parts connected therewith to the normal, Fig. 1, position.
- 40 The paper feeding mechanism embodied in the present construction includes a plurality of aligned paper feed rollers 66, arranged to coact with the top of the platen and with work sheets introduced from the rear of the platen through the channel 37. Said feed rollers 66 coact with said sheets 45 after the latter have passed above and beyond the printing line. The paper feed rollers 66, as shown in the present instance, are constructed and mounted in the same general manner as in said hereinbefore mentioned application. Thus, the feed rollers are 50 mounted for longitudinal adjustment along a supporting rod or spindle 67, supported at its ends by forwardly extending arms 68 that are pivotally supported on the platen frame. 55 Springs 68^a exert their force against the arms 68 and thus cause the feed rollers 66 to bear against the platen, or certain only of the work sheets thereon. By swinging the spindle 67 upward and rearward the said feed rollers 60 are released.

In the present machine we have included certain novel features relating to mounting adjusting and controlling the front paper feed roller and also have included certain of the means disclosed in said prior application 65

by which the paper deflector 47, line indicator 60, the ribbon vibrator 17 and end stops are automatically controlled thereby. In some instances we have modified such mechanism, and in other instances we have 70 combined therewith new features, as will now be described.

In the present construction we have provided a pair of outside margin paper feed rollers 69 and one or more inside or intermediate paper feed rollers 70 which coact with the platen above the printing line. Each of these feed rollers is constructed, mounted and controlled in part in a like manner, and the description of one such feed 75 roller and its mounting and control will apply to the others, except as hereinafter specifically pointed out. Referring more particularly to Figs. 7, 8 and 9, it will be seen that each of the feed rollers 69 and 70 is 80 mounted to turn on a pivot 71 received between and riveted to two parallel roller carrying arms or slides 72. Each pair of slides 72 thus connected are supported for rectilinear movement fore and aft of the machine by 85 and between a pair of supporting arms 73. In accordance with the present invention each of the supporting arms 73 is pivoted to turn on a rock shaft 74 and is confined within a guide slot between two companion bracket arms 75 that project up from a support or bracket 76 substantially C-shaped in cross section at the base thereof. This support is mounted on the cross head 77 of a bar 78 that is substantially T-shaped in cross section and extends substantially throughout 90 the length of the carriage in front of the platen. Screws 79 secure the bar 78 to the front cross bar 3 of the carriage. In this manner each support 76 together with the 95 parts carried thereby is mounted for adjustment as a single unit longitudinally of the bar 78. This is in order to provide for a separate adjustment of each of the feed rollers 69 or 70 together with the controlling members associated therewith to different points longitudinally of the platen, and thereby adjust such parts for use with various widths of ledger and invoice sheets and to the different positions lengthwise of the 100 platen in which such sheets are to be correlated. In order to secure each of the brackets or supports 76 in the position to which it is adjusted along the bar 78 a set screw 105 80 is threaded into the base of each bracket 120 and bears at its front end against the face of the cross head 77. By loosening a screw 80 the companion bracket 76 is freed for longitudinal adjustment along the bar 78.

It has been hereinbefore pointed out that 125 each of the supporting arms 73 is pivotally supported at its front end on the rock shaft 74, which in turn is supported near its ends for rocking movement by bracket plates 81 and 82, secured by screws 83 to the carriage, 130

as indicated in Fig. 2. This rock shaft is held against longitudinal displacement by a collar 84 held by a set screw 85 on said shaft outside the bracket plate 82 and by a hub 86 held on the shaft by screws 87 and 88 outside the bracket plate 81. The hub 86 has an arm 89 secured thereto, said arm terminating in what may be termed a main or primary finger piece 90 by which the shaft 74 may be rocked to control the feed rollers 69 and 70 and other parts in a manner which will hereinafter appear. Each of the supporting arms 73 has a depending arm 73^a (Figs. 7, 8 and 9) provided with an inwardly projecting ear 91 so that each member comprising the parts 73, 73^a and 91 is in the nature of a bell crank lever pivoted on the rock shaft 74. Each ear 91 is apertured at 92 to loosely receive therethrough a headed pin 93 which is in the nature of a shouldered and headed screw received at its threaded end in a tapped opening in the base of the companion bracket 76. A rather heavy coiled expansion spring 94 surrounds each pin 93 and bears at one end against the head of the pin and at the other end against the rear face of the companion ear 91. The force of each pair of springs 94 is thus exerted to force the associated ears 91 against the base of the companion bracket 76, as shown in Fig. 8, and thus said springs tend to hold the companion and connected pair of supporting guide arms 73 against pivotal movement around the rock shaft 74 until the force of said springs is overcome in a manner which will presently appear. The rear end portion of each supporting arm 73 is slotted at 95 to receive a headed guide pin 96 operatively connected with one of the arms 72 to support and guide it at its rear end. The forward end portion of each arm 72 is slotted at 97 to receive the rock shaft 74 therethrough, and thus support and guide each arm 72 at its forward end. The shouldered stem of each of the guide pins 96 passes loosely through a circular opening in the associated arm 72 and is riveted at its inner end to one end of a toggle arm 98. The other end of each toggle arm or member 98 is pivoted at 99 to one end of a companion toggle arm or member 100 or 101, such toggle arms for the outside feed rollers 69 being designated as 100, whereas such toggle arms for the intermediate feed rollers 70 are designated by the reference numeral 101. As shown in Fig. 10 each of the toggle arms 100 for the feed rollers 69 has a projection or spline 102 that is received in a substantially V-shaped spline groove 103 in the rock shaft 74. By these means the toggle arms 100 are all connected to rock with the shaft 74 without, however, interfering with the adjustment longitudinally of said shaft, of the associated supports 76 and the parts carried thereby, including the arms 100. From an inspection of Fig. 11 it will be understood that each of the toggle

arms 101 for the intermediate feed roller or rollers 70 has no splined connection with the rock shaft 74 but has a pivotal bearing thereon so that said arms 101 are free to turn on the shaft independently thereof, and the shaft is free to be rocked without rocking said arms. It will be seen that the pivots 99 uniting the toggle arms 98 with the companion arms 100, or 101 as the case may be, constitutes a tie rod between the two sets of toggle arms for each feed roller 69 or 70 and causes them to move together. Each pair of toggle arms 101 are, however, further united by a cross rod 104, which constitutes a finger piece by which the companion toggle members 98 and 101 may be moved from the broken (Fig. 8) position to the substantially straight-line position indicated in Figs. 1 and 9 to separately apply each of the feed rollers 70 to the platen.

From what has been said it will be understood that a rearward movement of the finger piece 90 from the Fig. 3 position is effective to rock the shaft 74 and straighten the toggles for both of the outside feed rollers 69. This results in moving the feed rollers 69 from front to rear with substantially a rectilinear sliding movement along the guide and supporting arms 73 until said feed rollers reach the platen above the printing line, or the work sheet with which said feed rollers coat. During this movement of the feed rollers 69 the springs 94 will maintain the guide arms 73 against pivotal movement around the rock shaft 74. When, however, the feed rollers 69 reach the curved surface of the platen they will be forced by the further straightening toggles to ride up on the platen a short distance, the curved surface of the platen at this time acting as a cam. The effect of this is that the guide arms 73 will receive an upward swinging movement around the rock shaft 74 against the resisting force of the springs 94. The reaction of said springs at this time will force the rear ends of the guide arms 73 down and apply the feed rollers 69 to the platen with a spring pressure, while the toggles are maintained in a substantially dead center position and prevent a breaking of the toggles until the finger piece 90 is moved forward. In practice it is preferable to shift the toggles slightly past the dead centered or straight line position where they are arrested by stops 105 on the arms 73. It will be seen, therefore, that the feed rollers 69 are applied to the platen with a strong spring pressure exerted only after the feed rollers reach the platen and when the guide arms 73 receive a pivotal movement due to forcing the feed rollers to ride on the curved surface of the platen during the final portion of the straightening of the toggles. As above indicated the feed rollers 69 are simultaneously withdrawn from the platen to a considerable distance 130

in front thereof, as shown in Fig. 3, by a forward movement of the finger piece 90, the springs 94 restoring the guide arms 73 to normal position as soon as the feed rollers 69 are freed from the platen. This gives ample space between said feed rollers and the platen to enable work sheets to be readily introduced into the channel 36 from in front of the platen.

The feed rollers 70 are applied in the same manner as that above described except that each feed roller 70 is separately applied, in the construction as thus far described, by an independent actuation of each of the finger pieces 104. The purpose of this individual application of each of the feed rollers 70, in some instances, will hereinafter appear.

It is desirable to automatically withdraw the intermediate feed rollers 70 with the outer feed rollers 69, whether one or more intermediate feed rollers be employed, and whether or not each of a plurality of intermediate feed rollers 70 be separately applied. To this end we provide for each feed roller 70 a crank or actuating arm 106 (see Figs. 8 and 9) that extends rearward from a hub 107, that surrounds the rock shaft 74, intermediate associated bracket arms 75 of the companion carrier 76. This hub is tapped to receive two pointed screws 108 and 109, the ends of which extend into the spline groove 103 of the rock shaft, the screw 108 coacting with one inclined side wall of the groove and the other screw 109 coacting with the opposite inclined wall of the groove, as shown in Figs. 8 and 9. By this construction a backing up of one screw and a threading in of the other screw will effect a rotative adjustment of the associated hub 107, thus elevating or depressing the companion actuating arm 106. This brings the rear end of the actuating arm, which underlies the companion tie rod 99 closer to or further from said rod and thus regulates or times the breaking of the associated toggles by the actuating arm 106 as the latter is elevated from the Fig. 1 position by a forward movement of the finger piece 90 from the Fig. 1 to the Fig. 3 position. The result of this movement of the finger piece 90 is to effect a clockwise movement of the shaft 74 together with all of the actuating arms 106, causing a withdrawal of all of the feed rollers 70 simultaneously with the withdrawal of the feed rollers 69, notwithstanding each of the rollers 70 may be separately applied.

It will be understood, of course, that a tightening of both screws 108 and 109 after the requisite adjustment of the associated arm 106 has been attained will hold the hub and arm firmly on the shaft 74 against both rotative and longitudinal movement thereon. When, however, a feed roller 69 or 70 is to be adjusted longitudinally of the platen a slight backing up of one of the associated screws

108 or 109 will release the hub 107 and its arm for adjustment along the shaft 74 with the associated support 76 and the other parts carried thereby, so that all of such parts may be adjusted as a single unit. After the adjustment last mentioned has been attained the loosened screw 108 or 109 will be again tightened and the parts will be ready for use.

The hub 86 to which the arm 89 and finger piece 90 are secured is connected to the shaft 74 by the two screws 87 and 88 in the same manner that each pair of screws 108 and 109 connect the companion hub 107 to said shaft. This manner of connecting the hub 86 to the shaft provides for effecting a rotative adjustment of the arm 89 to different set positions on the shaft and consequently regulates or times the actuation of other parts controlled by said arm, and which will be presently described. Said means for connecting the arm 89 to the rock shaft also enables it to be readily placed on the shaft and to be removed when desired as, for example, when the shaft is to be removed and one of the carriers 76 for an intermediate feed roller 70, together with the parts carried thereby, is to be removed from or placed in position on the shaft. In this connection it will be understood that in some instances a single intermediate feed roller 70 and associated parts may be employed, although there is provided a wider range of use when a plurality, say, two feed rollers 70 are employed as shown, as will presently appear.

We employ in the present construction automatically controlled paper end stops, such as are disclosed in said prior application, and which are intended to coact with the bottom edges of a rearwardly introduced bill sheet and the accompanying carbon sheet introduced in the channel 36. While the stop construction is the same as disclosed in said prior application there are employed in the present construction novel means for automatically controlling said stops. Such stop construction will now be described.

We prefer to employ two automatically controlled end stops, though any suitable number may be employed. Inasmuch as each of these stops is mounted, adjusted and controlled in a like manner the description of one will apply to both. A supporting strip 112 which is preferably made of spring metal is secured by suitable means to the back of the paper table 38 near the upper end thereof. The supporting strip 112 extends down in the rear of the paper table and has its lower end portion curved at 113 to conform generally to the curvature of the paper deflector 33. This curved portion of the supporting strip has a slot 114, as best shown in Figs. 3 and 5, that extends lengthwise thereof and fore and aft of the machine. A paper end stop 115, in the nature of a pin, is provided with a reduced, threaded, shank or

stem that extends through the slot 114 in the supporting strip and receives thereon, back of the strip, a washer 116 and a binding nut 117. The stop pin when thus secured in place is adapted to pass through a slot 118 in the deflector 33 and across the channel or passage 36 between the deflectors 32 and 33, as indicated in Fig. 1, this being the normal position of said stop to which it is pressed by the force of the spring carrying strip. This construction enables the stop 115, when its nut 117 is loosened, to be adjusted fore and aft of the machine in a curved path around the platen, such path conforming generally to the curvature of the deflectors 32 and 33 and the intermediate channel 36 between them, and into and out of which channel the stop moves in any position to which the stop may be adjusted. After the stop has been adjusted on its carrier to the desired position, a tightening of the nut 117 will secure the stop in place thereon. The means just described affords a rather wide range of adjustment of the stops to accord with bill sheets, checks, etc. of different depths.

The supporting strip 112 has off-set from one side of the lower portion thereof a depending finger or arm 119, as best shown in Figs. 3 and 5. This arm projects into the path of a finger 120 secured to a crank arm 121, the hub 122 of which is secured by a set screw 123 to a rock shaft 124. This shaft extends throughout the length of the carriage and has reduced ends received in bearing openings in the end plates 8 and 9. When the shaft 124 is turned clockwise in Fig. 1, the stop 115 is withdrawn to the ineffective, Fig. 3, position against the spring force of the stop-carrying spring strip. When the shaft 124 is released a light spring 125 tends to return said shaft to normal position, thereby enabling the stop 115 to be projected by its spring carrier to the operative, Fig. 1, position.

It will be understood that in the present instance we have provided two end stops 115 and companion supports and releasing devices therefor. These stops are aligned and located at a distance apart such as is required to coact with and arrest the comparatively narrow bill and carbon sheets B and B' respectively and accurately gage them.

The rock shaft 124 by which stops 115 are controlled is itself controlled by the following means:

A crank arm or actuating arm or member 126 has a hub 127 secured to the rock shaft 124 by a set screw 128. This member is substantially U-shaped in outline so as to pass around the platen shaft and provide a contact edge or stop 129 which normally coacts with the collar or hub 130 on the left-hand platen head to arrest said member and the parts controlled thereby in normal position, as shown in Fig. 1. A second contact edge

or stop 131 on the member 126 coacts with the opposite side of the hub 130 to limit the movement of the member in the opposite direction, as shown in Fig. 3. The upper arm of the actuating member 126 is slotted longitudinally at 132 to receive a headed pin 133 on the rear end of a link 134. The forward end of the link 134 is pivotally connected to a headed pivot pin 135 riveted to a second link 136 which extends forward and upward where it makes pivotal connection at 137 with the arm 89. The pivot pin 135 in extending from the link 136 to the link 134 passes through a guide slot 138 in a rear extension of the bracket plate 81. Said bracket plate in addition to being secured to the carriage by a screw 83 is connected thereto by a supporting link 139 supported at its lower end on the pivot pin 51. It follows from the foregoing that the point of pivotal connection between the links 134 and 136 will be guided by the pivot pin 135 working in the slot 138 to move in a straight line fore or aft of the machine when the finger piece 90 is actuated, depending on whether said finger piece is moved forward or backward. It also will be understood from an inspection of Figs. 1 and 5 that a spacing sleeve 140 which surrounds the pivot pin 135 constitutes an abutment or contact device that in the movement of the feed rollers under control of the finger piece 90 to ineffective position, or from the Fig. 1 to the Fig. 3 position, will engage the arm 57 and shift it and the parts controlled thereby. This results in automatically lowering the ribbon vibrator 17, in shifting the line indicator 60 from effective to the ineffective, Fig. 3, position and in shifting the front deflector 47 from the ineffective to the effective, Fig. 3, position. In addition to this, this same movement of the finger piece 90 results in moving the link 134 forward and, after a preliminary extent of lost motion, picking up the arm 126 and shifting the stops 115 from the effective to the ineffective Fig. 3 position. This automatic shifting of the end stops 115 to ineffective position when the feed rollers 69 and 70 are withdrawn and the machine is otherwise conditioned to receive a rearwardly introduced comparatively long and wide ledger sheet L, is in order to allow the bottom end of the ledger sheet to pass rearwardly beyond said stops. The extent to which the ledger sheet may thus be introduced past the end stops 115 may be determined by registering a given portion or line of the ledger sheet with the line indicator 60 or may be determined by special end stop mechanism such for example as that disclosed in the application of Frederick A. Hart, Sr. No. 172,685 filed March 4, 1927. It should be observed that when the feed rollers 69 are applied to the platen the arm 126 may be actuated at will by a finger pie

126^a carried thereby to move the end stops 115 to ineffective position. This is occasionally required when, for example, the end stops 115 are adjusted for use in gaging comparatively short bill sheets and it may be necessary now and then to introduce a longer or deeper bill form. By temporarily holding the end stops 115 in ineffective position by the finger piece 126^a, the longer bill form may be introduced past the end stops 115 and gaged with reference to the printing line and the previously introduced ledger sheet with the aid of the line indicator 60. After the ledger sheet has been introduced and adjusted a shifting of the finger piece 90 in the reverse direction will restore all of the parts except the feed rollers 70 (which must be independently applied) to the Fig. 1 position. It will be understood, however, that when the parts are in the Fig. 1 position, the finger piece 59 may be independently actuated to shift the deflector 47, the line indicator 60 and the ribbon vibrator 17 to Fig. 3 position while the stops 115 remain in effective position, and that such shifted parts will remain in shifted position only as long as the operator holds the finger piece 59 against the force of its returning spring 64. This is in order that the machine may temporarily be conditioned to receive a comparatively narrow bill sheet B and its accompanying carbon sheet B' in the channel 36, and enable them to be properly gaged and positioned by the end stops 115 while the feed rollers 69 remain in clamping engagement with the previously introduced wider ledger sheet L and hold it against movement. When this is effected the feed roller or rollers 70 are applied, holding the bill sheet in position. The machine is then in condition to proceed with the writing and a single written entry will appear in appropriate positions on the properly correlated bill sheet, the ledger sheet and the register sheet, the entries on the last two sheets being manifold copies produced with the aid of the carbon sheets B' and R'. It sometimes occurs that a narrow strip or bill sheet should have two separate entries written thereon, say for example, one directly under another and that these entries should appear on the ledger and record sheets at different places widthwise of each of these two last mentioned sheets. By providing, say, two independently applied feed rollers 70 adjusted longitudinally of the platen to positions where either one or the other will effectively coact with the narrow bill sheet, whether the latter be inserted to overlie the ledger sheet, say, near one or the other side edge thereof, the entries may be made as indicated above. Thus, a narrow bill sheet and accompanying carbon sheet may be inserted in proper correlation with the ledger sheet, say, near the left-hand edge thereof. A single feed roller 70 coacting therewith may

be applied to the bill sheet to hold it while an entry is being written thereon and a manifold copy thereof produced near the left-hand side of the ledger sheet. The applied feed roller 70 may then be released and the bill sheet and its accompanying carbon sheet withdrawn and shifted to overlie the right-hand side portion of the ledger sheet. The second feed roller 70 at this point may then be applied to hold the newly positioned bill sheet and carbon sheet in place where the next entry will appear below the previously written entry on the bill sheet, although such two entries will appear on the ledger sheet at different points widthwise thereof, on, say, the same cross line. However, it may for many purposes suffice to employ a single feed roller 70 separately applied and released in the manner hereinbefore described.

For certain purposes, or in some instances, where a plurality of feed rollers 70 are employed that may be individually adjusted to different positions longitudinally of the platen, as has been pointed out, it may be found desirable to couple said rollers together so that they may be applied by a single operation. Such a construction is shown in Figs. 12 and 13 wherein the finger piece or rod 104^a may be lengthened and extend loosely through bearing openings in the toggle arms 101^a of a plurality of feed rollers 70, or of all of said feed rollers. The rod may have detachably connected collars 141 at the ends thereof which prevent the accidental detachment of the rod from said toggle arms but does not interfere with the independent adjustment of each of the supports 76 for the rollers 70, together with the parts carried by such support, longitudinally of the platen. In this construction all of the feed rollers 70 may be simultaneously applied with the aid of the finger piece or rod 104^a, whereas the actuating arms 106 simultaneously release all of said feed rollers, as hereinbefore described.

Thus far we have described the means for effecting an application of the feed rollers 69 and 70 to the platen and for withdrawing them from the platen, as well as the automatic control of the ribbon vibrator 17, the deflector 47, line indicator 60 and end stops 115 by the shifting of the feed rollers 69 under control of the finger piece 90, and also have described the independent control of such parts by the finger pieces 59 and 126^a. However, in accordance with our present invention there remains a further and different control of the parts under certain conditions which will now be described.

Assume that the parts are in the Fig. 3 position and that the ledger sheet L has been introduced rearwardly into channel 36 past the end stops 115. It is desirable at this time to have the line indicator 60 in effective position, especially when end stops such as

are disclosed in said Hart application are not employed and the line indicator alone is depended on to properly position the ledger sheet in a line feed direction. It also is desirable at this time that the introduced ledger sheet shall be lightly held against accidental displacement, but nevertheless is free from clamping engagement of the coacting feed rollers 69 with the platen. In order to attain these ends it is merely necessary to shift the secondary finger piece 59 rearward from the Fig. 3 position, to the position indicated in Fig. 4. The extent of this movement is determined by two stops 142 and 143 which are adjustably mounted on the inner face of the bracket plate 81 and extend in the path of movement of the arm 57 and arrest it. Each of the stops 142 and 143 is in the nature of a screw stud having an eccentric stem 144 (see Figs. 1, 4 and 5) that receives a bearing in an opening in the bracket plate 81 and extends freely therethrough to the outside of said plate where it is threaded to receive a binding nut 145 by which the associated stop is held in the rotative position to which it may be adjusted.

The rearward shifting of the secondary finger piece 59 from the Fig. 3 to the Fig. 4 position not only results in shifting the deflector 47, line indicator 60 and ribbon vibrator 17 from the Fig. 3 to the Fig. 4 position, but also results in the arm 57 coacting with the contact sleeve 140 so as to shift the links 134 and 136 rearward a definite predetermined distance, determined by the arrest of the arm 57 by the stop 142, as shown in Fig. 4. This results in tending to restore the stops 115 under their spring pressure to normal position where they will bear lightly against the previously introduced ledger sheet and tend to hold it against accidental displacement. Such rearward shifting of the links 134 and 136 also results in displacing the arm 89 to the Fig. 4 position and in moving the feed rollers 69 close to but out of contact with the platen, as shown in Fig. 4. This is in order that the feed rollers may bear lightly against the ledger sheet without, however, clamping it against the platen so that the ledger sheet may if necessary receive accurate adjustment with the aid of the line indicator. At this time the parts will remain in the positions to which they have been shifted, leaving both hands of the operator free to adjust the ledger sheet, if this be necessary. After such adjustment is attained the operator moves the primary finger piece 90 rearward to the limit of its movement, thus applying the feed rollers 69 to the platen and firmly clamping the ledger sheet in place. The finger piece 59 may now be moved forward and temporarily held in such position to condition the machine to receive the sheets B and B' which are gaged or positioned in a line feed direction by the end stops 115, which at this time are in effec-

tive position. After the sheets B and B' are inserted and adjusted the feed roller or rollers 70 are applied to hold them in position, the finger piece 59 is released and the machine is conditioned to proceed with the writing.

70

We prefer to employ a spring-pressed detent device to hold the finger piece 90 and the parts controlled thereby against accidental displacement from the Fig. 3 position, due primarily to the reaction of the spring 64 which is stressed at this time. This we attain by extending the arm 89 below the shaft 74 to provide an arm 146 having a dwell 147 at its lower edge that is concentric with the shaft 74 and also having an angular or flat retaining face or edge 148. A detent 149 is pivoted at 150 to the outer side of the bracket plate 81. A coiled contraction spring 151 is connected at one end to a pin 152 on the plate 81 and is connected at the other end to a pin on the tail end of the detent. The engaging nose of the detent has a flat edge or face 153 which coacts with the face 148, as shown in Fig. 4, to retain the parts against accidental displacement under force of the spring 64. Rearward pressure exerted on either of the finger pieces 90 or 59 is, however, sufficient to disengage the detent against the reaction of its spring 151 after which the nose of the detent will ride on the dwell 147, as shown in Figs. 1 and 4.

75

From an inspection of Fig. 2 it will be understood that the inner sliding arm 72 of the left-hand feed roller 69, when the latter is in effective position, constitutes a side edge gage for the sheets B and B'. It will be understood, moreover, that when such sheets are introduced, the feed rollers 70 have been withdrawn from effective position, whereas, the feed rollers 69 have been applied to the ledger sheet, thereby conditioning the parts so that the arm 72 in question may properly function as a side edge gage for the sheets B and B'. The fact that the support 76 for the left-hand feed roller 69 (together with the parts carried by said support) is individually adjustable, enables the said arm 72, which acts as a side edge gage, to be adjusted to proper position to coact with the sheets B and B'.

100

Any suitable means may be employed other than the spacing blocks 34 and 35 to act as side gages for the sheets R and R'. In Fig. 2 we have shown a side gage 154 mounted on the spindle 67 for adjustment longitudinally thereof with the aid of a set screw 155.

105

One manner of using the devices of the present invention is as follows:

110

Assume that a register sheet R (Fig. 2) and its accompanying outside carbon sheet R' have been introduced through the channel 37 and properly positioned with the leading edges thereof beneath their feed rollers 66, and that the remaining parts are in the Fig. 3 position. The operator then introduces a

120

125

130

ledger sheet L from the front of the platen into the channel 36 and accurately adjusts or positions said sheet, with the aid of the line indicator 60 if desired, as hereinbefore indicated. After such adjustment of the ledger sheet an actuation of a finger piece 90 in a rearward direction results in straightening the toggles for the rollers 69 to the Fig. 8 position and applying the feed rollers 69 against the platen and against the margins of the previously introduced ledger sheet. At this time the feed rollers 70 are in the released position, as shown in Fig. 8. The bill or statement sheet B with an accompanying carbon sheet B' may then be introduced from the front of the platen into the channel 36, and between the feed rollers 70 and the platen, or the ledger sheet thereon, as previously pointed out. After the statement sheet and the accompanying carbon sheet have been properly adjusted, with the aid of the end stops 115, the feed rollers 70 are shifted rearward by the operator from the Fig. 8 position. This results in applying said feed rollers 70 to the previously adjusted bill or statement sheet B. The machine is then conditioned to proceed with the writing, and the matter written will be produced on the statement sheet and through the carbon sheets on the ledger and register sheets.

After the "statement" is written as described, the operator shifts the finger piece 90 to the Fig. 3 position, thereby releasing the feed rollers 69 and 70 and permitting ready withdrawal of the statement sheet, the accompanying carbon sheet and the ledger sheet, and conditioning the machine to receive new sheets to replace those withdrawn.

If it be assumed that end stops, such as those disclosed in said Hart application, are employed, and that the parts are in the Fig. 3 position, then three operations of the parts are required to prepare the machine for making another entry, as follows:

- 45 1st. Move the finger piece 90 to the Fig. 1 position after the ledger sheet is introduced.
- 2nd. Temporarily shift the parts controlled by the finger piece 59 to the Fig. 3 position with the aid of said finger piece, and
- 50 3rd. Apply the feed roller or rollers 70 to the bill sheet after it has been introduced with the accompanying carbon sheet.

The operator may then proceed with the writing.

55 It will be understood that each of the feed rollers 70, its finger piece 104, its support 76, its actuating arm 106 and the intermediate connections by which said feed roller is actuated from said arm 106 and by the finger piece 104 may be detached from the remaining parts. Therefore, such parts may be applied or omitted, depending on the use to which the machine is to be put, as a two-sheet or three-sheet biller, or for other uses such as 60 have been hereinbefore indicated.

In substantially the same manner as hereinbefore pointed out the machine may be employed as a check-writing machine, at which time the sheet described above as a "register sheet" would constitute a manifold record of the checks written and may constitute a "pay roll sheet". In this event, however, no ledger sheet will be employed. The feed rollers 69 will be employed to coat with the checks, leaving the feed rollers 70 ineffective, or omitting them from the machine.

Generally speaking, the sheet R described above as a "register sheet", and which remains in the machine when the other sheets are removed and new ones inserted, may constitute a "register sheet", a "proof sheet", a "sales sheet", a "distributing sheet", or a "pay roll sheet", depending on the use of the machine for different purposes.

In some instances the line indicator 60 may be employed to position, in a line feed direction, each sheet introduced from in front of the platen into the channel 36 when it is not feasible or desirable, for one reason or another, to employ end stops, or to employ end stops to coat with a sheet corresponding to the ledger sheet.

By the present invention we have provided a construction which has proved rapid of operation, highly efficient and reliable in use, which is compact and comparatively simple in construction and can be manufactured at comparatively small cost and be readily embodied in Remington machines without modifying, or materially modifying, the existing structural features of said machines.

The claims in this case are specific to features not disclosed in either of said hereinbefore mentioned applications.

Various changes may be made in the construction and certain parts thereof may be employed without others, without departing from our invention as it is defined in the accompanying claims.

What we claim as new and desire to secure by Letters Patent, is:

1. The combination of a platen, a pair of margin feed rollers, means for simultaneously moving said margin feed rollers together in their movements to and from the platen, a plurality of intermediate feed rollers, and means for individually shifting each of said intermediate feed rollers to the platen, said last mentioned means comprising a pair of toggles for each of said intermediate feed rollers, and means for straightening the pair of toggles for each intermediate feed roller independently of the toggles for the other intermediate feed roller or rollers and thus 115 separately apply said intermediate rollers.

2. The combination of a platen; a pair of margin feed rollers; means for simultaneously moving said margin feed rollers together in their movements to and from the platen;

- a plurality of intermediate feed rollers; means for individually shifting each of said intermediate feed rollers to the platen, said last mentioned means comprising a pair of toggles for each of said intermediate feed rollers, and means for straightening the pair of toggles for each intermediate feed roller independently of the toggles for the other intermediate feed roller or rollers and thus separately apply said intermediate rollers; and means for simultaneously breaking all of said straightened toggles when said margin feed rollers are moved away from the platen, thereby simultaneously releasing said margin feed rollers and such of the intermediate feed rollers as have been applied.
3. The combination of a platen, a pair of margin feed rollers, means for simultaneously moving said margin feed rollers together in their movements to and from the platen, a feed roller intermediate said margin feed rollers, means for individually moving said intermediate feed roller to the platen, means for adjusting said intermediate feed roller to different positions longitudinally of the platen, and means for automatically releasing said intermediate feed roller from the platen when the margin feed rollers are released.
4. The combination of a platen, a pair of margin feed rollers, means for separately adjusting each of said pair of margin feed rollers longitudinally of the platen, means for simultaneously moving said margin feed rollers together in their movements to and from the platen, a feed roller intermediate said margin feed rollers, means for individually moving said intermediate feed roller to the platen, means for adjusting said intermediate feed roller to different positions longitudinally of the platen, and means for automatically releasing said intermediate feed roller from the platen when the margin feed rollers are released.
5. The combination of a platen, a rock shaft having a spline groove extending longitudinally thereof, a finger piece for rocking said shaft, a paper feed roller support adjustable longitudinally of the platen, a paper feed roller carried by said support, devices including a toggle for shifting said feed roller to and from the platen, said devices being adjustable longitudinally of the platen with said support and feed roller, and a spline-like projection on a member of said toggle seated in said spline groove to cause such member and the rock shaft to rock together but affording an adjustment of said toggle member with said support.
6. The combination of a platen, a rock shaft, a finger piece for rocking said shaft, margin feed rollers controlled in their movements to and from the platen by a rocking of said shaft, an actuating arm fixed to rock with said shaft, an intermediate feed roller

movable to the platen independently of said margin feed rollers, controlling means for thus applying said intermediate feed roller, said controlling means when the intermediate feed roller is applied being brought into cooperative relation with said arm to be actuated thereby, whereby a rocking of said shaft will simultaneously release the independently applied intermediate feed roller as well as the margin feed roller, and means for adjusting said intermediate feed roller, its controlling means and said actuating arm longitudinally of said rock shaft.

7. The combination of a platen, a paper feed roller, and means for controlling the shifting of said feed roller comprising a rock shaft, an actuating arm thereon, and splined connecting means between said actuating arm and shaft that enables an angular adjustment of said arm around the axis of the shaft to be effected as well as an adjustment of the arm along the shaft without destroying the splined connection between said shaft and actuating arm.

8. The combination of a platen, a paper feed roller, and means for controlling the shifting of said feed roller comprising a rock shaft having a spline groove with sloping side walls therein, an actuating arm having a hub that surrounds said shaft, and screws threaded into said hub and extending into said groove and cooperative with the sloping side walls thereof to hold the arm in the position to which it may be adjusted along said shaft and also to provide for adjusting the arm to different angular positions around the axis of said shaft and for holding the arm in the angular position to which it may be adjusted.

9. The combination of a platen, a feed roller, and means for controlling the movement of said feed roller into and out of contact with the platen comprising a toggle the straightening of which applies the feed roller to the platen, a rock shaft, a crank arm on said rock shaft cooperative with said toggle, a splined connection between said rock shaft and crank arm that affords an angular adjustment of the crank arm around the axis of the shaft as well as longitudinally thereof, a finger piece for straightening said toggle to apply said feed roller, and a second finger piece for rocking said shaft to break said toggle with the aid of said crank arm and thus withdraw the feed roller from the platen.

10. The combination of a platen; a plurality of independently applied feed rollers; means associated with each of said feed rollers for separately applying it to the platen comprising a toggle, and a separate finger piece independently operated to straighten the associated toggle; another or primary finger piece; and means controlled thereby for simultaneously breaking all of

the straightened toggles of the separately applied feed rollers and simultaneously withdrawing them from the platen.

11. The combination of a platen; a plurality of independently applied feed rollers; means associated with each of said feed rollers for separately applying it to the platen comprising a toggle, and a separate finger piece independently operated to straighten the associated toggle; another or primary finger piece; a plurality of margin paper feed rollers; means controlled by said primary finger piece for applying said margin feed rollers to and withdrawing them from the platen; and means controlled by said primary finger piece for simultaneously breaking all of said toggles of the separately applied feed rollers and withdrawing them from the platen with said margin feed rollers.

12. The combination of a platen; a plurality of independently applied feed rollers; means associated with each of said feed rollers for separately applying it to the platen comprising a toggle, and a separate finger piece independently operated to straighten the associated toggle; another or primary finger piece; a plurality of margin paper feed rollers; means controlled by said primary finger piece for applying said margin feed rollers to and withdrawing them from the platen including a rock shaft; and a plurality of crank arms on said rock shaft, one for each of said separately applied feed rollers and which are operative to simultaneously break the toggles of all of such separately applied feed rollers and withdraw the latter from the platen with the margin feed rollers.

13. The combination of a platen; a plurality of independently applied feed rollers; means associated with each of said feed rollers for separately applying it to the platen comprising a toggle, and a separate finger piece independently operated to straighten the associated toggle; another or primary finger piece; a plurality of margin paper feed rollers; means controlled by said primary finger piece for applying said margin feed rollers to and withdrawing them from the platen including a rock shaft; a plurality of crank arms on said rock shaft, one for each of said separately applied feed rollers and which are operative to simultaneously break the toggles of all of such separately applied feed rollers and withdraw the latter from the platen with the margin feed rollers; and means for affording an adjustment longitudinally of the platen of each of said separately applied feed rollers, its associated toggle and crank arm as a single unit.

14. The combination of a platen; a paper feed roller mounted for adjustment longitudinally of a platen; and controlling means for shifting said feed roller comprising a

toggle, a hand controlled rock shaft, and a splined connection between said toggle and the rock shaft that enables the toggle to be adjusted longitudinally of the platen with said feed roller without destroying the operative connection between the rock shaft and toggle.

15. The combination of a platen; a plurality of paper feed rollers each mounted for independent adjustment longitudinally of the platen; and controlling means for simultaneously shifting said feed rollers comprising a pair of toggles for each of said feed rollers, and a splined connection between one member of each pair of said toggles and the rock shaft that enables each pair of toggles to be adjusted longitudinally of the platen with the associated feed roller without destroying the operative connection between said toggles and the rock shaft.

16. The combination of a platen, a paper feed roller shiftable into and out of contact with the platen, a guide on which said feed roller is supported to slide in such shifting movement, a spring which tends to resist a movement of the guide, and a manually controlled toggle for shifting said feed roller on said guide into and out of contact with the platen and for overcoming the force of said spring when the toggle is straightened and the feed roller applied to the platen, thus causing the spring to exert its force against the feed roller and hold it applied to the platen under a spring pressure.

17. The combination of a cylindrical platen, a paper feed roller, a spring-pressed movable support on which said feed roller is shiftable to and from the platen in a direction that affords a camming action of the feed roller against the curved surface of the platen when applying the feed roller thereto, whereby said support is moved against the force of its spring by such camming action, and a manually controlled toggle for shifting said feed roller on its support and which when straightened applies the feed roller to the platen.

18. The combination of a cylindrical platen, a paper feed roller, a spring-pressed movable support on which said feed roller is shiftable to and from the platen in a direction that affords a camming action of the feed roller against the curved surface of the platen when applying the feed roller thereto, whereby said support is moved against the force of its spring by such camming action, and means that enable said feed roller and support to be adjusted as a single unit to different positions longitudinally of the platen.

19. The combination of a cylindrical platen, a paper feed roller, a spring-pressed movable support on which said feed roller is shiftable to and from the platen in a direction that affords a camming action of the feed roller against the curved surface of the platen

when applying the feed roller thereto, whereby said support is moved against the force of its spring by such camming action, a manually controlled toggle for shifting said feed roller on its support and which when straightened applies the feed roller to the platen, and means that enable said feed roller toggle and support to be adjusted as a single unit to different positions longitudinally of the platen.

20. The combination of a cylindrical platen, a paper feed roller, a movable guide on which said feed roller is shifted to and from the platen, spring means for holding said guide against movement while the feed roller is thus shifted, and manually controlled positively applied controlling means for shifting the feed roller and by which the feed roller is caused to ride on the curved surface of the platen after making contact therewith and thereby shift said guide against the force of said spring means and cause such force to be exerted against the feed roller.

21. The combination of a cylindrical platen, a paper feed roller, a movable guide on which said feed roller is shifted to and from the platen, spring means for holding said guide against movement while the feed roller is thus shifted, and manually controlled positively applied controlling means for shifting the feed roller and by which the feed roller is caused to ride on the curved surface of the platen after making contact therewith and thereby shift said guide against the force of said spring means and cause such force to be exerted against the feed roller, said manually controlled means including a toggle which when straightened overcomes the force of said spring means as specified.

22. The combination of a platen, a plurality of outside margin paper feed rollers movable in unison to and from the platen, one or more intermediate paper feed rollers movable individually to the platen, an independently operable pair of toggles for each of said individually applied feed rollers and a straightening of each pair of which toggles applies the associated feed roller only, manually controlled means for simultaneously withdrawing the margin feed rollers from the platen, and automatically operating means controlled by said manually controlled means for breaking said toggles and withdrawing the individually applied feed roller or rollers when the margin feed rollers are withdrawn.

23. The combination of a platen, paper feed rollers, primary controlling means for shifting said feed rollers to and from the platen, and auxiliary or secondary controlling means for shifting said feed rollers from a released position to a position comparatively close to but out of contact with the platen and incapable of moving said feed rollers to contact with the platen.

24. The combination of a platen, paper feed rollers, manually controlled means for shift-

ing said feed rollers towards and from the platen comprising a finger piece by an actuation of which said feed rollers may be moved into contact with the platen, a second finger piece for moving said feed rollers from a released position towards the platen, and a stop for arresting said second finger piece when the feed rollers reach a predetermined position close to but out of contact with the platen.

25. The combination of a platen, paper feed rollers, manually controlled means for shifting said feed rollers towards and from the platen comprising a finger piece by an actuation of which said feed rollers may be moved into contact with the platen, a second finger piece for moving said feed rollers from a released position towards the platen, a stop for arresting said second finger piece when the feed rollers reach a predetermined position close to but out of contact with the platen, and means for adjusting said stop so as to vary the point of arrest of said second finger piece and thus vary the distance the feed rollers may be shifted to in their approach to the platen under control of said second finger piece.

26. The combination of a platen, paper feed rollers, controlling means for shifting said feed rollers from a released position to a position comparatively close to but out of contact with the platen and incapable of moving said feed rollers to contact with the platen, a paper deflector, and automatically operating means for shifting said deflector from an effective to an ineffective position by an actuation of said controlling means to position the feed rollers close to but out of contact with the platen.

27. The combination of a platen, paper feed rollers, controlling means for shifting said feed rollers from a released position to a position comparatively close to but out of contact with the platen and incapable of moving said feed rollers to contact with the platen, a line indicator, and automatically operating means for shifting said line indicator from an ineffective to an effective position by an actuation of said controlling means to position the feed rollers close to but out of contact with the platen.

28. The combination of a platen, paper feed rollers, controlling means for shifting said feed rollers from a released position to a position comparatively close to but out of contact with the platen and incapable of moving said feed rollers to contact with the platen, a ribbon vibrator, and automatically operating means for shifting said vibrator to normal position by an actuation of said controlling means close to but out of contact with the platen.

29. The combination of a platen, paper feed rollers, controlling means for shifting said feed rollers from a released position to a position comparatively close to but out of contact with the platen and incapable of mov-

ing said feed rollers to contact with the platen, a paper deflector, a line indicator, and automatically operating means for shifting said deflector from an effective position to an ineffective position and for shifting said line indicator from an ineffective to an effective position by an actuation of said controlling means to shift the feed rollers close to but out of contact with the platen.

30. The combination of a platen, paper feed rollers, controlling means for shifting said feed rollers from a released position to a position comparatively close to but out of contact with the platen and incapable of moving said feed rollers to contact with the platen, a paper deflector, a line indicator, a ribbon vibrator, and automatically operating means for shifting said deflector from an effective to an ineffective position for shifting said line indicator from an ineffective to an effective position and for shifting said ribbon vibrator to normal position by an actuation of said controlling means to shift the feed rollers close to but out of contact with the platen.

31. The combination of a platen, paper feed rollers, controlling means for shifting said feed rollers from a released position to a position comparatively close to but out of contact with the platen and incapable of moving said feed rollers to contact with the platen, normally effective paper end stops, and automatically operating means for shifting said end stops to ineffective position by an actuation of said controlling means to shift the feed rollers close to but out of contact with the platen.

32. The combination of a platen, paper feed rollers, manually controlled means for shifting said feed rollers towards and from the platen comprising a finger piece by an actuation of which said feed rollers may be moved into contact with the platen, a second finger piece for moving said feed rollers from a released position to a predetermined position close to but out of contact with the platen and incapable of moving said feed rollers to contact with the platen, a paper deflector to aid in introducing work sheets into the machine, and automatically operating means actuated by the manual operation of either of said finger pieces selectively in one direction to shift said deflector from an effective to an ineffective position.

33. The combination of a platen, paper feed rollers, manually controlled means for shifting said feed rollers towards and from the platen comprising a finger piece by an actuation of which said feed rollers may be moved into contact with the platen, a second finger piece for moving said feed rollers from a released position to a predetermined position close to but out of contact with the platen and incapable of moving said feed rollers to contact with the platen, a line indicator, and automatically operating means operated by

the manual operation of either of said finger pieces selectively in one direction to shift said line indicator from an ineffective to an effective position.

34. The combination of a platen, paper feed rollers, manually controlled means for shifting said feed rollers towards and from the platen comprising a finger piece by an actuation of which said feed rollers may be moved into contact with the platen, a second finger piece for moving said feed rollers from a released position to a predetermined position close to but out of contact with the platen and incapable of moving said feed rollers to contact with the platen, a paper deflector to aid in introducing work sheets into the machine from in front of and beneath the platen, a line indicator, and automatically operating means actuated by the manual operation of either of said finger pieces selectively in one direction for shifting said deflector from an effective to an ineffective position and for shifting said line indicator from an ineffective to an effective position.

35. The combination of a platen, paper feed rollers, manually controlled means for shifting said feed rollers towards and from the platen comprising a finger piece by an actuation of which said feed rollers may be moved into contact with the platen, a second finger piece for moving said feed rollers from a released position to a predetermined position close to but out of contact with the platen and incapable of moving said feed rollers to contact with the platen, a paper deflector to aid in introducing work sheets into the machine from in front of and beneath the platen, a line indicator, a ribbon vibrator automatically shiftable during the shifting movement of said deflector into and out of normal position, and automatically operating means actuated by the manual operation of either of said finger pieces selectively in one direction for shifting said deflector across the printing line from an effective to an ineffective position, for shifting said line indicator from an ineffective to an effective position and for restoring said ribbon vibrator to normal position.

36. The combination of a platen, paper feed rollers, controlling means for shifting said feed rollers into and out of contact with the platen including a finger piece, a shiftable paper deflector to aid in a rearward introduction of work sheets from in front of and beneath the platen, a second finger piece, means controlled thereby for at will shifting said deflector into and out of effective position independently of said feed rollers when the latter remain applied to the platen, and intermediate operative actuating connections between said finger pieces that enable said feed rollers to be shifted from a withdrawn position to a position close to but out of contact with the platen and no further during an

actuation of said second finger piece to shift said deflector from an effective to an ineffective position.

37. The combination of a platen, paper feed rollers, controlling means for shifting said feed rollers into and out of contact with the platen including a finger piece, a shiftable paper deflector to aid in a rearward introduction of work sheets from in front of and beneath the platen, a line indicator shiftable to indicating position when said deflector is shifted to ineffective position and vice versa, a second finger piece, means controlled thereby for thus shifting said deflector and line indicator independently of said feed rollers when the latter remain applied to the platen, and intermediate operative connections between said finger pieces that enable said feed rollers to be shifted from a withdrawn position close to but out of contact with the platen and no further during the actuation of said second finger piece to shift said deflector and line indicator.

38. The combination of a platen, a plurality of feed rollers, a manually controlled rock shaft, toggles connecting said feed rollers and rock shaft for applying the feed rollers to and withdrawing them from the platen; a paper deflector to aid in introducing a work sheet rearward from in front of and beneath the platen; means for automatically shifting said deflector into and out of effective position including operative connections between said deflector and said rock shaft, and a spring for moving the deflector to ineffective position; an arm on said rock shaft; and a spring-pressed detent coacting with said arm to resist the force of said spring when the feed rollers are withdrawn and the deflector is in effective position.

39. The combination of a platen, a paper feed roller shiftable into and out of contact with the platen, a guide on which said feed roller is supported to slide in such shifting movement, hand controlled means for positively applying said feed roller to the platen and for locking the feed roller against retractive movement when thus applied, and a spring which tends to resist a movement of the guide and is overcome when the feed roller is positively applied to the platen and locked against retractive movement by said hand controlled means and thereby exerts its force against the feed roller to apply it to the platen.

40. The combination of a platen, a paper feed roller normally free from spring pressure and shiftable into and out of contact with the platen, a pivoted guide on which said feed roller is supported to slide in such shifting movement, hand controlled means for positively applying said feed roller to the platen and for locking the feed roller against retractive movement when thus applied, and a spring which tends to resist the pivotal

movement of the guide and is overcome and permits a rocking of the guide when the feed roller is applied to the platen by said hand controlled means and thereby exerts its force against the feed roller to apply it to the platen.

41. The combination of a cylindrical platen, a paper feed roller, a spring-pressed movable support on which said feed roller is shiftable to and from the platen in a direction and to an extent that affords a camming action of the feed roller against the curved surface of the platen when applying the feed roller thereto, whereby said support is moved against the force of its spring by such camming action, and hand controlled means for thus moving said feed roller and applying it positively to the platen and holding the feed roller thus applied against retractive movement.

42. The combination of a cylindrical platen, a paper feed roller, a spring-pressed pivoted guide and support on which said feed roller is mounted for substantially rectilinear sliding movement to and from the platen in a direction and to an extent that affords a camming action of the feed roller against the curved surface of the platen when applying the feed roller thereto, thereby causing said guide and support to be given a pivotal movement against the force of its spring so that such force is exerted to hold the feed roller against the platen, and manually controlled shifting and holding means for effecting such rectilinear movement of the feed roller and for holding it forced against the platen and from retractive rectilinear movement away from the platen.

43. The combination of a cylindrical platen; a paper feed roller; and a spring-pressed movable support on which said feed roller is shiftable bodily to and from the platen in a direction and to an extent that affords a camming action of the feed roller against the curved surface of the platen when applying the feed roller thereto, whereby said support is moved against the force of its spring by such camming action, said support comprising a pair of parallel angular levers between which said feed roller is received and by which the roller is supported and guided in its bodily movement to and from the platen, a spring which tends to resist a pivotal movement of each of said levers and the force of which is overcome by the application of the feed roller to the platen and hand-controlled means for forcibly effecting such bodily movement of the feed roller against the platen and for holding it against return movement on said levers.

44. In a typewriting machine, the combination of a platen, and means for collating work sheets in the machine comprising paper feed rollers, and hand-controlled means for

shifting said feed rollers from a position remote from the platen to a position sufficiently close thereto to coact with and aid in holding a work sheet against the platen but with freedom from pressure of the feed rollers against the platen so as to enable such work sheet to be easily adjusted, said hand-controlled means being incapable of moving said feed rollers into contact with the platen.

35 **30** Signed at the borough of Manhattan, city of New York, in the county of New York and State of New York, this 22nd day of September, A. D. 1927.

FREDERICK A. HART.
SIGURD L. WALSOE.
